ENVELOPE CONSTRUCTION

John L. Knight, 5526 Fire Fly St., Houston, Tex.
Filed July 18, 1958, Ser. No. 749,385
4 Claims. (Cl. 235—61.12)

This invention relates to new and useful improvements in envelope constructions.

This application is a continuation-in-part of application Serial No. 704,442, filed December 23, 1957, now abandoned.

Heretofore, efforts have been made to provide envelope constructions which were capable of being automatically sorted as to destination by mechanical or electronic business machines of the key punch type. However, so far as is known, such prior efforts have been confined to envelope constructions in which key punch openings were provided on a side extension of the envelope. With such prior constructions, the area for the key punch designators or openings is necessarily limited to prevent the envelopes from becoming excessively long. On the other hand, if it is attempted to increase the area for the key punch openings while keeping the length of the envelope approximately the usual size of standard envelopes, then the pocket area for the letter in such prior envelope constructions is extremely small. Therefore, a letter must be folded until it becomes small enough to fit into the envelope pocket, but then the letter is relatively thick and bulky in the envelope and such additional thickness may interfere with the use of the envelope in the usual mechanical or electronic business machines.

It is therefore an object of this invention to provide a new and improved envelope construction which is approximately the usual size of standard envelopes and which has a maximum area for punch-out designators while at the same time providing an envelope pocket of a size substantially the same as provided in standard envelopes, whereby a maximum number of designations is possible with the punch-out designators in the envelope without requiring an excessive length for the envelope or a folding of letters placed in the envelope pocket into a greater thickness than required for standard envelopes.

An important object of this invention is to provide a new and improved envelope in which the full length of the envelope is utilized, both at the top and bottom thereof, for punch-out designators to indicate the destination or similar information, whereby the maximum number of such punch-out designators may be placed in a row at the top and bottom of the envelope.

Another object of this invention is to provide a new and improved envelope construction in which a strip is provided at the top, bottom, and both sides of the envelope for punch-out designators, whereby an envelope of substantially standard size has a sufficient area in such strips to provide punch-out designators for each State of the United States, a large number of the cities in the particular state of destination, and the postal zone number for the destination of the letter, whereby the letter may be readily sorted for delivery automatically by conventional mechanical or electronic business machines of the key-punch type.

A further object of this invention is to provide a new and improved envelope construction in which punch-out designators are positioned in a row along each edge of the envelope so that the designators which are punched out are readily detected by their relationship to the edge of the envelope, and therefore even the most simple types of known mechanical or electronic business machines may be used for sorting the envelopes.

The preferred embodiment of this invention will be described hereinafter, together with other features there-

2

of, and additional objects will become evident from such description.

The invention will be more readily understood from a reading of the following specification and by reference to the accompanying drawings forming a part thereof, wherein an example of the invention is shown, and wherein:

FIG. 1 is a plan view of the envelope construction of this invention in a position prior to the folding of the various sections together;

FIG. 2 is a plan view of the envelope construction of this invention as viewed from the back side thereof; and

FIG. 3 is a fragmentary view of the left hand lower corner of FIG. 2 in an enlarged form to more fully illustrate the preferred type of punch-out designators used with the envelope construction of this invention.

In the drawings, the letter A designates generally the envelope construction of this invention. The envelope construction A is preferably made from a single sheet of paper or similar material and it includes a front section B having folds 10, 11, 12, and 14 (shown in dotted lines in FIG. 1) at the edges thereof. As will be explained more in detail hereinafter, a back section C, a closure flap D and side flaps E and F are joined or are otherwise connected to the front section B at the folds 12, 10, 11 and 14, respectively. A narrow border is provided around the envelope construction A with designators which are adapted to be punched out, as will be more fully explained, so that a person using the envelope A or handling same may punch out the desired designator or designators for indicating the destination of the envelope A or other information in connection with such envelope A.

Considering the invention more specifically, the front section B has a border or rectangular frame of adhesive such as common glue formed on its inner surface, and such border of adhesive is formed by an adhesive band 11a positioned inwardly of the fold or fold line 11 (FIG. 1), an adhesive band 10a formed inwardly of the fold or fold line 10 (FIG. 1), an adhesive band 12a formed inwardly of the fold or fold line 12 (FIG. 1); and an adhesive band 14a formed inwardly of the fold or fold line 14 (FIG. 1). An adhesive band 10b is provided on the closure flap D outwardly of the fold or fold line 10, and such band 10b is preferably of the same width as the band 10a so that when the closure flap D is folded along the fold 10 to the position shown in FIG. 2, the adhesive bands 10a and 10b overlap and are coextensive with each other. Similarly, an adhesive band 11b is formed on the side section E outwardly of the fold or fold line 11. Such adhesive band 11b is preferably of the same width as the adhesive band 11a so that it overlies and is substantially coextensive with the band 11a when the end section E is folded on the fold 11 to the position shown in FIG. 2. Also, an adhesive band 12b is formed on the back section C adjacent to the fold 12 and outwardly thereof. Such band 12b is preferably substantially the same width as the band 12a and is preferably substantially coextensive therewith so as to overlie the band 12a when the back section C is folded on the fold 12 to the position shown in FIG. 2. Likewise, an adhesive band 14b is provided on the side section F adjacent to the adhesive band 14a and outwardly of the fold 14. The band 14b is preferably the same width and is substantially coextensive with the band 14a so as to overlie same when the side section F is folded on the fold 14 to the position shown in FIG. 2.

To form the border or narrow band around the envelope A as shown in FIG. 2, the closure flap D, side flap E, back section C and side section F are folded from the position shown in FIG. 1 of the drawings along the folds 10, 11, 12 and 14, respectively, so as to bring the ad-

hesive bands 10a, 11a, 12a, and 14a on the inside of the front section B into contact with the adhesive bands 10b, 11b, 12b, and 14b, respectively. The overlapped bands 10a and 10b are thereby secured together because of the adhesive surfaces on such areas 10a and 10b so as to form an upper strip 20 which extends from the fold 10 (FIG. 2) to the dotted line 20a shown in FIG. 2 which is the end of the adhesive areas 10a and 10b. The strip 20 extends for substantially the full length of the envelope A and does not interfere with the folding back of the closure flap D along a fold line which is coincident with the dotted line 20a. A side strip 21 is formed by the folding of the side section E along the fold 11 to overlap the adhesive bands 11a and 11b so that the bands become secured or adhered to each other. The strip 21 extends from the fold 11 to the dotted line 21a which represents the inner ends of the bands 11a and 11b when they are adhered or secured to each other. A side strip 22 is formed by the folding of the side section F on the fold 14 so as to cause the adhesive bands 14a and 14b to overlap for the adhering or securing thereof together. The strip 22 extends from the fold 14 inwardly to the dotted line 22a in FIG. 2 which is representative of the inner edges of the adhesive bands 14a and 14b. A lower strip 23 is formed by folding the back section C on the fold 12 to overlap the adhesive bands 12a and 12b. The strip 23 extends from the fold 12 to the dotted line 23a shown in FIG. 2 which is representative of the inner ends of the bands 12a and 12b.

In order to form an envelope pocket in the envelope construction A inwardly of the strips 20, 21, 22 and 23, the back section C is adhered or otherwise secured to the side sections E and F. Preferably, an adhesive area 27 is provided along one side of the inner surface of the back section C so that when it is overlapping with a portion of the side section E as shown in FIG. 2, the back section C is adhered to the side section E. Similarly, another adhesive area 28 is provided on the other side (the right side as viewed in FIGS. 1 and 2) of the inner surface of the back section C for adhering to the end section F when it overlaps with a portion thereof as shown in FIG. 2. The closure flap D is normally provided with a gummed area 30 on its inner surface (FIG. 1) which is preferably made adhesive by moistening same in the known manner so that when a letter or other object is placed within the envelope pocket defined by the end sections E and F and the back section C, the closure flap D can be sealed to the end sections E and F and the back section C to confine the letter or other object within the envelope pocket.

For preventing an excess of paper or other material at the corners of the envelope A which are adhered together to form the respective strips 20, 21, 22 and 23, the adjacent edges of such strips are cut so that they are in substantially abutting contact rather than overlapping with each other. Thus, the edges 10c and 11c are cut at an angle of approximately 45° with respect to the fold 11 so that when they are brought adjacent to each other (FIG. 2) they are in abutting relationship and are not overlapping. Likewise the ends or edges 11d and 12c are cut on an angle of 45° with respect to the fold 11 but at an opposite angle to the angle on which the ends 10c and 11c are cut (FIG. 1). The ends or edges 11d and 12c also abut with each other and do not overlap as shown in FIG. 2 when the sections C and E are folded to form the envelope and the strips 21 and 23. Also, the ends or edges 12d and 14c are cut on an angle of about 45° with respect to the fold 14 so that they are in abutment and do not overlap when the sections C and F are folded to form the strips 22 and 23 (FIG. 2). The ends or edges 10d and 14d are cut at an angle of about 45° with respect to the fold 14 and are at an opposite angle with respect to the angle formed by the ends 12d and 14c so that when such ends or edges are brought adjacent to each other as shown in FIG. 2, they are in an abutting relationship and are not overlapping.

The strip 20 is formed with a plurality of punch-out designators 35 which are preferably formed in a single row that is aligned length-wise of the envelope A. The strip 23 is formed with a plurality of punch-out designators 36 which are also preferably in a row which is aligned length-wise of the envelope A and is substantially parallel with the row of the punch-out designators 35 formed in the strip 20. The strip 21 is formed with a plurality of punch-out designators 37 which are formed in a row preferably and which extend for the full height or width of the envelope A. Similarly, a plurality of punch-out designators 38 are formed or are provided in the strip 22 and they are preferably aligned in a row which extends for the full height or width of the envelope A. Various types of punch-out designators can be used for the designators 35, 36, 37, and 38, so long as they are capable of being punched out to form an opening completely through both thicknesses of the material such as the paper forming the two sides of each of the strips 20, 21, 22 and 23.

20 A typical punch-out designator which may be used with the envelope construction A of this invention is shown in detail in the enlarged view of the left hand lower corner of the envelope construction A as shown in FIG. 3 of the drawings. Thus, as seen in FIG. 3, each of the punch-out designators 36 and 37 shown therein is identical, and it will be understood that preferably the punch-out designators 35 and 38 (FIG. 2) would also be identical with the designators 36 and 37 shown in FIG. 3. Therefore, for an understanding of the construction of such designators, reference will be made to only the construction of the designators 36 shown in FIG. 3. Each designator 36 has sides 36a, 36b, 36c and 36d, all of which are completely cut through both thicknesses of the paper or other material forming the strip 23, except for the pointed projections 36e, 36f, 36g and 36h, respectively, which remain secured to the strip 23. Therefore, in order to remove a designator 36, a pencil or even the finger of the person may be used for punching the designator 36 so as to tear loose projections 36e, 36f, 36g and 36h for removing the 40 particular designator 36 to leave an opening in the strip 23.

For purposes of illustration, one of the designators 36 is shown as having been punched out in FIG. 2 and to form an opening 36'. Similarly, one of the designators 37 is indicated as having been punched out to form an opening 37' and one of the designators 35 has been punched out to form an opening 35'.

In the preferred use of the envelope construction of this invention, the designators 35 would be used for designating the States of the United States, the designators 36 would be used for designating the city of destination of the letter, as will be more fully explained, and if desired the additional designators 38 on the strip 22 can also be used for designating cities. The designators 37 would preferably be used for designating the postal zone of the destination of the letter. It will be observed that the envelope construction A as illustrated in FIG. 2 has more than enough designators 35 in the strip 20 for the States in the United States, and therefore a portion of such designators 35 at one end thereof may be used for designating foreign countries, provinces, or additional cities if so desired.

The designators 35, 36, 37 and 38 would normally have a number or other symbol adjacent to each designator such as indicated in FIG. 3 where the numerals 1, 2, 3 and 4 appear adjacent to the designators 36 and where the numerals 24, 25 and 26 appear adjacent to the designators 37. If the designators are to be punched out by the sender of the envelope, rather than some one in the postal system, then each sender would have code charts so as to correlate the numbers on the designators with the States, cities and zones throughout the United States.

For example, the code chart would list the States of the United States and possibly foreign countries or provinces with the corresponding numbers as printed on the strip 75 20 adjacent to the designators 35. Therefore, the punch-

ing out of a particular one of the designators 35 such as indicated at 35' in FIG. 2 would indicate that the destination of the envelope was to a particular State represented by that number on the code chart. For each State, there would be a separate chart listing the cities of that State in relationship to the numbers adjacent to the designators 36 and also preferably the designators 38, so that there would be an extremely large number of cities possible in each State for designation. Therefore, if a particular city in a State is picked such as indicated at 36' in FIG. 2, the number opposite that punched out opening would indicate on the chart which city was being designated. Similarly, the zones would be designated by punching out one of the designators 37 such as indicated at 37'.

If the postal system does the punching out of the designators, then the code charts would be retained and used by the postal employees and the senders of the envelopes would not need to know the code and the sender would not do the punching out of the designators. In fact, the punching out of the designators could even be accomplished by a machine or machines.

In any event, when the desired designators have been punched out, the envelope along with other envelopes having similar designators would be run through a conventional mechanical or electronic business machine to first separate or sort the letter as to the State of destination. The letters which are sorted as to States may then be sent to a central receiving station in each State of destination and there the letters may be sorted by similar business machines as to cities and zones. Or, it will be appreciated that if desired the letters can be initially sorted both as to State, city and zone and then forwarded to the city destination for distribution.

Various other types of information may be incorporated by changing the code charts used in conjunction with the envelope construction A so that the numerals adjacent to each of the designators represent a different designation or information. For example, if it was desired to use the strip 20 of designators 35 for designating the same information as the strip 23 of designators 36, the designators 35 would be staggered laterally or length-wise with respect to the designators 36 as shown in FIG. 2 so that a single machine could pick up the designations which were punched out in either of the strips 20 or 23. However, normally it will not be necessary to stagger the designators 35 and 36 with respect to each other.

The foregoing disclosure and description of this invention is illustrative and explanatory thereof and various changes in the size, shape and materials, as well as in the details of the illustrated construction, may be made within the scope of the appended claims without departing from the spirit of the invention.

What is claimed is:

1. In an envelope construction having a sheet of flexible material having a front section, a back section joined to the lower edge of said front section and having a fold therebetween, a closure flap joined to the upper edge of said front section and having a fold therebetween, and a side section joined to each side of said front section and having a fold between each side section and said front sec-

tion, the improvement residing in, adhesive means securing a narrow portion of said front section and a narrow portion of said back section together along the fold therebetween to form a lower strip, adhesive means securing a narrow portion of said front section and a narrow portion of said closure flap together along the fold therebetween to form an upper strip, adhesive means securing a narrow portion of said front section and a narrow portion of each side section together along the respective folds between each side section and said front section to form a side strip on each side of the envelope, said back section and said end sections having overlapped portions, means securing said overlapped portions together to form an envelope pocket confined by said lower strip, upper strip and side strips, said closure flap having an adhesive surface which is adapted to be contacted with the upper portions of the back section and side sections for closing said envelope pocket to seal a letter therein, and a single row of perforated punch-out designators formed in each of said lower strip, upper strip, and side strips for designating the destination or other information in connection with a letter or the like transmitted in said envelope.

2. The envelope construction set forth in claim 1, wherein the edges of the side sections, back section and closure flap which are adjacent to each other at each corner formed at the intersection of the lower strip, upper strip and side strips are in abutting relationship to prevent the forming of a greater thickness at such corners than throughout the rest of the strips whereas the portions of the edges of the side sections, back section and closure flap which extend inwardly from the lower strip, upper strip, and side strips overlap with each other to form the envelope pocket.

3. The envelope construction set forth in claim 1, wherein the punch-out designators are aligned in a row on each of said lower strip, upper strip, and side strips.

4. The envelope construction set forth in claim 1, wherein the punch-out designators are aligned in a row along the upper strip and the punch-out designators are aligned in a row along the lower strip, and wherein at least a portion of the punch-out designators in the row along the upper strip are staggered with respect to at least a portion of the punch-out designators in the row along the lower strip.
